(57) **CLAIM**

I claim the ornamental design for a connector plug, as shown and described.

DESCRIPTION

FIG. 1 is a front perspective view of a connector plug of the present invention;

FIG. 2 is a front view thereof, the rear view being a mirror image;

FIG. 3 is a first side view thereof;

FIG. 4 is a second side view thereof;

FIG. 5 is a top view thereof; and,

FIG. 6 is a bottom view thereof.

The broken line in the figure drawings is included for the purpose of illustrating environment and forms no part of the claimed design.
